CLAIM

The ornamental design for a non-spouted base faucet, as shown.

DESCRIPTION

FIG. 1 is a perspective view of a non-spouted base faucet. FIG. 2 is a perspective view of a non-spouted base faucet. FIG. 3 is a perspective view of a non-spouted base faucet. FIG. 4 is a top plan view of a non-spouted base faucet. FIG. 5 is a bottom plan view of a non-spouted base faucet. FIG. 6 is a left elevation view of a non-spouted base faucet. FIG. 7 is a front elevation view of a non-spouted base faucet; and, FIG. 8 is a rear elevation view of a non-spouted base faucet. The broken lines shown in the drawings represent unclaimed portions of the faucet and forms no part of the claimed design.
